UNITED STATES PATENT OFFICE.

GEORGE C. COWLES, OF SAGINAW, MICHIGAN, ASSIGNOR TO GERMAIN BROTHERS COMPANY, OF SAGINAW, MICHIGAN, A CORPORATION OF MICHIGAN.

CLAMP.

1,404,275.

Specification of Letters Patent. Patented Jan. 24, 1922.

Application filed May 6, 1921. Serial No. 467,449.

To all whom it may concern:

Be it known that I, GEORGE C. COWLES, a citizen of the United States, residing at Saginaw, in the county of Saginaw and State of Michigan, have invented certain new and useful Improvements in Clamps; and I do hereby declare the following to be a full, clear, and exact description of the invention, such as will enable others skilled in the art to which it appertains to make and use the same.

This invention relates to clamps and pertains more particularly to furniture clamps and the like.

15 The objects of my invention are to provide a factory clamp adapted to a wide range of uses and capable of being quickly secured to and released from the work.

Another object of my invention is to provide a clamp made of a few simple parts requiring a minimum of machine work, the parts being so arranged that the capacity of the clamp can be readily increased or decreased by simply substituting for one common machine bolt another bolt of a different length.

Another object is to provide a clamp, the two shoes or working jaws of which need not be parallel with each other when in use, 30 but can be swung at an angle with respect to each other, in order to accommodate work that can not be properly held by a clamp having jaws in fixed parallel relation with each other.

35 A still further object of my invention is to provide in combination with the screw clamp a wedge that can be quickly driven into the final clamping position by means of a hammer or a maul, so that it is only necessary to run the screw adjustment of the clamp down until the work is approximately clamped and then with a blow of the hammer to drive home the wedge and thus complete the tightening of the clamp, 45 saving time in the operation.

Another object of my improvement is to provide in a clamp, the tension member of which consists of a common machine bolt, means to prevent the bolt from springing 50 and to prevent the jaws from losing their parallel relationship when engaging the work.

It frequently happens in the use of C-

clamps that the back of the clamp becomes sprung and the jaws open at an angle, so 55 that when a pile of work, as for example, a number of boards, are to be clamped, the pressure of the clamp sometimes causes the boards to be forced out, on account of the springing of the clamp faces.

60 My present invention, by providing long shanks on the working jaws, obviates this difficulty, for the shanks take against the back edges of the work and prevent the jaws from springing out of their parallel 65 relationship.

With the foregoing and certain other objects in view, which will appear later in the specification, my invention comprises the devices described and claimed and the equivalents thereof.

In the drawings, Fig. 1 is a side view of the clamp in use.

Fig. 2 is a rear view of the clamp shown in Fig. 1.

Fig. 3 is a top plan view of the same.

Fig. 4 is a view of the bolt.

Fig. 5 is a perspective view of the tightening wedge.

Fig. 6 is a perspective view of the upper 80 clamping shoe.

Fig. 7 is a perspective view of the lower clamping shoe.

As is clearly shown in the drawings, 1 represents the material being clamped between the lower clamping shoe 2 and the upper clamping shoe 3. The lower clamping shoe is removably secured to the head end of an ordinary machine bolt 4 and the upper clamping shoe 3 is slidably received 85 on the threaded end of the bolt. Beneath the lower beveled face of the upper shoe 3 is a transversely slidable wedge 5, the lower face of which is parallel with the face of the lower clamping shoe 2 and the upper face is 90 beveled to register with the beveled lower face of shoe 3.

6 is a wing nut or equivalent device threaded on the bolt 4 and taking against the upper end of the slidable shoe 3.

100 The lower clamping shoe 2 is formed with an integral upwardly projecting shank 7 having a longitudinal bore 8 to receive the bolt 4.

The shank 7 is adapted to take against the 105 work, as shown in Fig. 1, so that when

clamped the tendency for the working face of shoe 2 to spring or open will be reduced.

The shoe 3 is preferably formed with an integral downwardly extending shank 9—
5 see Fig. 6—which may be of square or rectangular cross section and formed with a longitudinal bore 10 to loosely receive the bolt 4.

11 is the forwardly projecting beveled working face of the upper clamping shoe 3.

12 is an elongated aperture formed in wedge 5, slidingly receiving the square shank 9 and adapted to permit the wedge to be driven transversely with respect to bolt
15 4, as indicated in Fig. 1.

The forward end of wedge 5 is preferably formed with an upwardly extending lug 13, which enables the wedge to be driven back to release the work, without liability of
20 striking the work with the driving hammer or maul.

The lower part of shank 9 is preferably formed with lateral integral projections 14, which can be bent outwardly, as indicated in
25 Figs. 1 and 6, after wedge 5 has been assembled on the shank 9, thereby preventing the two members from becoming separated.

The lower clamping shoe 2 may preferably be formed with downwardly projecting
30 ribs 15 spaced apart to receive the head of bolt 4 between them, and upon the lower parts of these ribs 15 I prefer to provide lugs 16, which may be integral with the ribs 15 and may be bent inwardly, as shown on
35 the left-hand rib of Fig. 2, after the bolt has been assembled on the clamping shoe 2. One or more of these projections may be provided, as shown in Fig. 2 and both of them may be bent to hold the bolt in place,
40 but I prefer to provide two projections and to bend only one of them, so that if the bolt 4 is changed for a longer, or shorter bolt, the other projection may be employed to hold the bolt in place, providing the first-
45 used projection has been broken.

By the means above described, I have produced a simple and effective clamping device that is especially adapted for rapid assembling and clamping of work in factory
50 production. Any one of the parts may be easily replaced without discarding the entire clamp, and since all of the parts are of standard construction, consisting mainly of unmachined castings, it is obvious that the
55 repair parts can be readily obtained at a minimum of expense.

When the clamp is used for rapid production work in factories, repeatedly clamping parts of approximately the same thickness,
60 it is sufficient to set the nut 6 in the desired position, and thereafter the clamping and unclamping may be done by the wedge 5 without disturbing the adjustment of the
65 nut.

Having thus described my invention, what

I claim and desire to secure by Letters Patent is:

1. In a clamp, the combination of a threaded bolt, a lower clamping shoe secured to the head of said bolt, an upper clamping shoe slidable on said bolt and formed with a lower beveled face, a wedge loosely received on and transversely slideable with respect to said bolt, said wedge formed with a beveled upper face engaging the beveled lower face of said upper clamping shoe, and a nut on the threaded end of said bolt. 70

2. In a clamp, the combination of a threaded bolt, a lower clamping shoe secured to the head of said bolt, an upper clamping shoe loosely received on said bolt and having a beveled lower face, a wedge apertured to loosely receive said bolt, the upper face of said wedge registering with the lower face 85 of said upper clamping shoe, a nut on said bolt engaging said upper clamping shoe, said lower clamping shoe formed on its lower side with ribs spaced apart to receive the head of said bolt between them, and lugs 90 carried by said ribs and adapted to be bent inwardly to form a retainer for the head of said bolt.

3. In a clamp of the class described, in combination, a lower clamping shoe, an upwardly projecting shank on said shoe, said shank formed with a longitudinal bore to receive the bolt of said clamp, projecting ribs on the lower part of said clamp, and bolt-
95 retaining lugs on said ribs. 100

4. In a clamp, the combination of a threaded bolt, a lower clamping shoe secured to the head end of said bolt, a wedge loosely received on said bolt, said wedge formed with an elongated aperture and a beveled upper face, an upper clamping shoe having an elongated square shank formed with a longitudinal bore loosely receiving said bolt, the lower face of said shoe beveled, and lateral projections on said shank operating as a 105 retainer for said wedge, and a nut on the threaded end of said bolt. 110

5. In a clamp of the class described, the combination of an upper clamping shoe having a forwardly extending projection and a beveled lower face, a square shank formed with a longitudinal bore, and a malleable projection on said shank, for the purposes set forth. 115

6. In a clamp, the combination of a threaded bolt, a lower clamping shoe secured to the head of said bolt, an upper clamping shoe having a beveled lower face and a square shank formed with a longitudinal bore to receive said bolt, an apertured wedge loosely received and transversely slideable on said shank, and a nut on the threaded end of said bolt. 125

7. In a clamp, the combination of a threaded bolt, a lower clamping shoe releas- 130

ably secured to the head of said bolt, an upper clamping shoe having a beveled lower face and a square shank formed with a longitudinal bore to receive said bolt, a malleable wedge-retaining projection on said shank, an apertured wedge loosely received and transversely slidable on said shank, an

upwardly projecting lug on the end of said wedge, and a nut on the threaded end of said bolt. ¹⁰

In testimony whereof, I affix my signature.

GEORGE C. COWLES.
